UNITED STATES PATENT OFFICE.

MICHELANGELO INCUTTI, OF KANSAS CITY, MISSOURI.

SHOE INNER BRACE.

Application filed November 3, 1928. Serial No. 317,042.

The present invention relates to stiffening and bracing means for boots and shoes, and aims to provide an improved device of this character adapted to be incorporated in the heel and shank portion of the shoe or applied in position after the same has been manufactured in a quick and convenient manner.

Accordingly I have devised a combined metal and leather appliance adapted to be placed next to the insole of the boot or shoe and extending from the heel counter and throughout the shank portion of the sole in such a manner as to afford the desired bracing and stiffening function, as required.

With this general object in view the invention will now be described by reference to the accompanying drawing illustrating one practical and efficient form of embodiment of my invention, after which the novel features therein will be set forth and claimed.

In the drawing—

Figure 1 is a longitudinal sectional view of a shoe provided with interior bracing means constructed in accordance with the present invention;

Figure 2 is a plan view of the same with the lining strip raised to disclose the improved device;

Figure 3 is a perspective view of the device removed from the shoe; and

Figure 4 is a section on line IV—IV of Fig. 1.

Referring now to said drawing in detail, the same illustrates the improved device as comprising a stiffening member 5 of suitable resilient metal, such as spring steel stamped out to produce the skeleton form shown in Figure 3 having the cut-out openings 6 to lighten its construction. The rear end of the stiffening or bracing member 5 is curved slightly upward and its front end curved slightly downward to adapt the same to conform to the contour of the inner sole 7 of a boot or shoe, wherein it is designed to be installed beneath the lining strip 8 and against the upper face of the insole 7.

Along its middle longitudinal line the bracing member 5 is grooved or corrugated to form a strengthening and stiffening rib 9 which tapers towards its front end, and the front end portion of the member 5 is also tapered off to make a smooth fit along the forward end of the shank portion of the shoe as shown in Figure 1.

At the opposite ends of the rib 9 the member 5 is provided with openings for rivets 10

or the like for attaching the same to a leather cushioning strip 12 which is also of a shape to conform to and fit within the shoe over the heel and shank portions thereof, the forward end of said strip 12 being also skived off at the junction of the shank and ball portions of the sole as shown in Figure 1. The upper face of the strip 12 is also suitably stamped or marked with a pattern 14 marking the outlines of the openings 6 of the metal bracing member 5 beneath, and thus serving as a convenient guide in nailing the device in place within the shoe.

In installing the device within a shoe (if placed therein after its manufacture), the heel 15 is first removed and the lining strip 8 raised as represented in Figure 2, after which the device is tacked upon the top face of the insole 7 preparatory to being permanently secured in place by means of nails 16 first driven from the outside through the heel portion of the sole, and thereafter by means of nails 17 driven from the inside of the shoe into the heel and shank portions of the sole. Certain of these nails 17 also serve to secure the heel 15 back in place and it will also be understood that the bracing device is worked and adjusted into smooth-lying position conforming snugly and accurately to the top of the insole during the process of driving the nails 16 and 17.

In the driving of the nails 17, the pattern 14 of course acts as a nailing guide indicating to the operator the location of the various openings 6 in the metal member 5 and hence the proper points at which to position the nails for driving the same.

In Figure 4 the view shown represents a section on the line IV—IV of Figure 1 with the exception that the device has not yet been entirely conformed to the heel seat; this view illustrates the function of the rib 9 as accommodating the device temporarily to the curvature of the heel seat; later, as the moisture applied to the leather beneath the brace in installing the device in place and thereafter in the wearing of the shoe, imparts a certain degree of sponginess thereto, the rib becomes embedded in the insole and the remainder of the device conforms gradually to the curvature of the underlying portions of the shoe as shown in Figure 1.

It is well known that shoes, especially those of the high-heel type illustrated herein, are prone to break down at the heel and get out of shape as they are worn, soon resulting in

the shoe becoming unsightly and unfit for further service. By strengthening and bracing the heel portion as herein provided for, such fault is effectively corrected. I am 5 aware of course that stiffening means of various kinds have been employed for this purpose, but the specific device herein described and illustrated, including the skeleton and ribbed plate of the peculiar form shown, is 10 believed to be new, and I therefore desire to reserve the right to make such changes or modifications as may fairly fall within the scope of the following claims.

What I claim is:—

- 15 1. A shoe inner brace comprising a skeleton stiffening and bracing member adapted to be positioned upon the upper face of the insole of the shoe, and a leather cushioning strip overlying said member and secured thereto, the upper face of said strip having a nailing guide or pattern comprising an outline corresponding to and indicating the outlines of the openings in said bracing member.
- 20 2. A shoe inner brace comprising a skeleton stiffening and bracing member adapted to be positioned upon the upper face of the insole of the shoe and of a size extending

from the rear end of the heel portion to the forward end of the shank portion of the shoe, and a leather cushioning strip overlying said member and secured thereto, the forward end portions of said member and strip being gradually tapered toward their forward edges, and the upper face of said strip having a nailing guide or pattern comprising an outline corresponding to and indicating the outlines 30 35 of the openings in said bracing member.

3. A shoe inner brace comprising a skeleton stiffening and bracing member adapted to be positioned upon the upper face of the insole of the shoe and provided with a longitudinal groove or corrugation forming a stiffening and strengthening rib extending the greater portion of the length of said member and tapering toward its forward end, and a leather cushioning strip overlying said member and secured thereto, the upper face of said strip having a nailing guide or pattern comprising an outline corresponding to and indicating the outlines of the openings 40 45 50 in said skeleton bracing member.

In witness whereof I hereunto affix my signature.

MICHELANGELO INCUTTI.
